US00D396696S

United States Patent [19]

Takagi et al.

[11] Patent Number: Des. 396,696

[45] Date of Patent: **Aug. 4, 1998

[54] SEMICONDUCTOR PACKAGE

[75] Inventors: **Yuichi Takagi; Kazuhiko Ueda**, both of Tokyo, Japan

[73] Assignee: **Sony Corporation**, Tokyo, Japan

[**] Term: **14 Years**

[21] Appl. No.: **65,264**

[22] Filed: **Jan. 30, 1997**

[51] LOC (6) Cl. **13-03**

[52] U.S. Cl. **D13/182**

[58] Field of Search **D13/182; 174/52.2-52.4; 206/710-719; 257/254, 659, 666, 678-697; 709, 730, 738, 780, 796; 437/183, 217, 220; 361/730**

[57] CLAIM

The ornamental design for a semiconductor package, as shown and described.

DESCRIPTION

FIG. 1 is a perspective view of a semiconductor package showing our new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a rear elevational view thereof;

FIG. 8 is a perspective view of another embodiment of a semiconductor package showing our new design; and,

FIG. 9 is a front elevational view of the embodiment of FIG. 8. The rest of views of the embodiment of FIG. 8 are the same as those of the embodiment of FIG. 1.
